Application September 1, 1955, Serial No. 532,012

19 Claims. (Cl. 99—174)

This invention relates to a display support for articles of irregular shape, such as ham butts or shanks, comprising a cradle adapted to fit such articles individually to provide an attractive display package that may be readily stacked, shipped and handled without damage to the displayed articles.

Hams are commonly split into butts and shanks and wrapped in transparent protective material to provide an attractive display package. Most retailers prefer to display the face side of ham butts and shanks to provide sales appeal. With hams wrapped in accordance with current practice it is impossible to stack the hams in more than a single layer and provide a neat, attractive display. In the case of self-service stores the additional problem of handling is involved. Many customers handle several ham butts or shanks in attempting to select the best, and replace the ones not selected in a very careless manner that may damage the wrapper. In cases where the wrapper is torn the hams discolor and require refacing and rewrapping if they are not sold soon. The expensiveness of mass display of ham butts and shanks is so great, because of the costs incidental to such damage, that many dealers make no attempt to display them, and thus the market potential of the products is decreased.

In accordance with the present invention, ham butts and shanks are wrapped in suitable transparent material and then secured in an individual cradle formed of corrugated board, fiber board, plastic or other suitable materials having adequate dimensional stability to support the weight of the ham butt or shank and to cushion it against damage due to friction or shock in transit or handling, so that each ham butt and shank is in condition for display when it reaches the retailer. The ham butt or shank is held in the cradle by pressure sensitive tape, cloth, or other suitable binding material.

The cradle may be made in several different styles, as hereinafter described, and each style will differ in its shape in accordance with its intended use, that is, whether it is to be used to support a ham butt or a ham shank. The particular shape of ham shanks makes it necessary to dimension the cradle to bring the center of the base panel as close as possible to the center of gravity of the ham shank in order to attain a position of maximum stability for the ham shank. A horizontal band of pressure sensitive tape is wrapped around both the cradle and the ham butt or shank as tightly as possible to prevent shifting of the ham relative to the cradle. A second band of tape is applied as tightly as possible in a vertical plane about the ham butt or shank and the cradle to help bind the cradle to the ham butt or shank. The positioning of the tapes along the center of gravity lines provides a package in which the weight of the ham does not cause any substantial structural pressure on the package. The cradle merely provides balance for the package and stability is attained with comparatively weak structural materials. Although the binding material is

2

preferably pressure sensitive tape, it may be gummed paper, shrinkable paper of film, wire, or string.

The structure by which the above and other advantages of the invention are attained will be described in the following specification, taken in conjunction with the accompanying drawings showing several preferred illustrative embodiments of the invention, in which:

Figure 1 is a perspective view of a display package with an irregularly shaped ham butt firmly held in a support cradle with the cut face of the ham exposed through a transparent, protective wrapping;

Fig. 2 is a cross sectional view of the support cradle, taken along the line 2—2 of Fig. 3, with the ham butt outlined in dotted lines;

Fig. 3 is a longitudinal sectional view of the cradle, taken along the line 3—3 of Fig. 2, with the ham butt outlined in dotted lines;

Fig. 4 is a cross sectional view, taken along the line 4—4 of Fig. 3;

Fig. 5 is a plane view of the blank from which the cradle of Fig. 1 is formed;

Fig. 6 is a fragmentary detail perspective view of one end of the blank partially folded into position to form the cradle;

Fig. 7 is a perspective view of the cradle for a ham butt as shown in Fig. 1;

Fig. 29 is a perspective view of the cradle of Fig. 27 in partially assembled position; and

Fig. 30 is a side elevational view of a ham shank secured in another embodiment of the cradle.

Referring to Figs. 5, 6 and 7, the blank for forming the cradle of Fig. 1 comprises a bottom panel 2, a pair of bottom reinforcing panels 3 and 4, a pair of end panels 5 and 6, and corner cushioning members 7, 8, 9 and 10. The blank is scored to provide two longitudinal fold lines 11 and 12 which refine the sides of bottom panel 2 and end panels 5 and 6. A transverse score provides a fold line 13 which separates end panel 5 from one end of bottom panel 2, and a similar fold line 14 separates end panels 6 from the opposite end of the bottom panel. A slit 15 extending from one edge of the blank to fold line 11 separates one end of bottom reinforcing panel 3 from corner member 7, and a similar slit 16 separates the opposite end of panel 3 from corner member 8. The ends of panel 4 are similarly separated from corner members 9 and 10 by slits 17 and 18, respectively.

As shown in Fig. 5, panels 3 and 4 are each shorter than bottom panel 2 and are centrally disposed relative to the bottom panel. Panel 3 is folded upwardly and inwardly to juxtapose it on panel 2, and panel 4 is folded upwardly and inwardly to juxtapose it on top of panel 3 to provide a bottom of triple thickness for the cradle. The blank is preferably of corrugated paper-board, and, although the reinforced bottom has considerable rigidity to prevent failure of the cradle in use, it has sufficient cushioning effect to protect a ham packaged therein. The end panels 5 and 6 are folded upwardly along lines 13 and 14, respectively, to extend upwardly at right angles to the opposite ends of panel 2.

The corner members 7, 8, 9 and 10 are duplicates, except that they are reversed, and therefore only one will be described in detail. Corner member 7 comprises a triangular side panel 19, a bottom flap 20, a trapezoidal panel 21, and a triangular flap 22. The right angle sides of panel 19 are separated from end panel 5 and bottom flap 20 by fold lines 11 and 23, respectively. Fold line 23 is aligned with fold line 13. Bottom flap 20 is separated from the outer edge portion of panel 2 by a slot 11' which coincides with fold line 11 and extends from slit 15 to fold line 23. The angular side of panel 19 terminates at a fold line 24 which defines one of the parallel sides of panel 21. Fold line 24 extends from fold line 11 to the outer end of fold line 23. The other parallel side of panel 21 is separated from corner flap 22 by a fold line 25.

After end panel 5 has been folded upwardly along fold line 13 at right angles to bottom panel 2, flap 20 is folded inwardly along fold line 23 and panel 19 is folded inwardly along fold line 11 to position flap 20 under one end of panel 2. Flap 20 is preferably secured to the underside of panel 2 by staples or some other suitable means, such as adhesive. Panel 21 is then folded inwardly along fold line 24 to form a cushioning member, and corner flap 22 is folded downwardly along fold line 25. Although we have described the folding operations relative to one corner member 7, it will be understood that all corner members may be folded simultaneously.

In the assembled position of the cradle, cushioning panels 21 extend angularly at the ends in spaced relationship to bottom panel 2 and end panels 5 and 6, so that when a ham butt 26 is positioned in the cradle, panels 21 will give slightly to allow them to conform to the irregular shape of the ham butt. The bottom round end of the ham butt is supported by the reinforced bottom of the cradle, and the sides of the ham are supported along opposite ends by cushioning panels 21 and end panels 5 and 6.

The ham butt is preferably sealed in a transparent protective wrapping 27 before it is seated in the cradle

with its cut surface exposed at top. A strip 28 of pressure sensitive tape or similar material is applied to the outside of the wrapped ham and the outer surfaces of end panels 5 and 6, as shown in Fig. 1. The ends of strip 28 are pulled tightly to cause the upper portions of end panels 5 and 6 to conform to the shape of the sides of the ham butt. A similar strip 29 is applied transversely across the top of the wrapped ham butt and the underside of bottom panel 2. Strips 28 and 29 are positioned to coincide with the center of gravity lines of the package so that the weight of the ham does not introduce any substantial structural pressure on the package, and stability is attained even when the cradle is made of structurally weak material. Strips 28 and 29 cooperate to prevent the ham from shifting in any direction relative to the cradle. The flat surface of the bottom of the cradle and the relative flat surfaces of end panels 5 and 6 of the completed package enable a plurality of packages to be packed closely together for storage or shipment without substantial waste space between the individual packages. Each cradle is sufficiently flexible to enable it to snugly fit any ham butt of approximately normal size, even though each ham butt may vary slightly in its dimensions.

The wrapping 27 is preferably transparent, but may be colored or printed to provide any desired decorative effect. The strips 28 and 29 may also be transparent, or may be colored to harmonize with or contrast with the exposed surface of the cradle to enhance the aesthetic appeal of the display package. Strips 28 and 29 may also be printed, if desired.

Although the cradle has been described in particular relationship to a ham butt, it should be understood that it may be used to support a ham shank or other irregularly shaped article. It may also be used merely as a supporting member where no display function is desired.

A ham packaged as described above has a very valuable advantage beyond the protection and the attractive display features that have already been mentioned. If the package is opened, any attempt to remove a substantial quantity of the ham will alter the size of the ham, relative to the cradle, so that the tampering will be obvious. This characteristic of the package makes it impossible for a retailer to cheat a customer by removing some of the choice slices of ham adjacent the cut face, and then selling the rest of the ham at the same price as if the choice slices were not removed.

In Figs. 8, 9 and 10 we have disclosed a very inexpensive type of cradle comprising a single strip 30 of corrugated board or other suitable material folded transversely to provide a bottom panel 31 at approximately the center of the strip and upstanding end panels 32 and 33 on opposite ends of the bottom panel. A panel 34 adjacent the opposite end of panel 32 is folded in juxtaposition to panel 32 and an outer panel 35 is positioned on top of the center portion of bottom panel 32 with a cushioning panel 36 disposed angularly between the ends of panels 34 and 35. A cushioning panel 37 extends angularly downwardly from the upper end of panel 33 and the other outer panel 38 extending from the lower end of panel 37 is juxtaposed on top of panel 35. Panels 35 and 38 are secured to bottom panel 31 by staples or adhesive to hold the cradle in position to receive a ham. The particular arrangement of panels 34, 36 and 37 adapts this cradle to receive a ham shank 39, as shown in Fig. 8. The ham shank is wrapped in transparent protective material as described in connection with the ham butt shown in Fig. 1, and is secured to the cradle by tapes 28 and 29.

The embodiment of Figs. 11, 12 and 13 is essentially the same as that of Figs. 8, 9 and 10 except that the cradle is adapted to receive a ham butt, and the outer panels are abutting instead of overlapping each other. A strip 40 is folded to provide a bottom panel 41, upstanding end panels 42 and 43, panels 44 and 45 folded down-

wardly against panels 42 and 43, respectively, angular cushioning panels 46 and 47, and outer panels 48 and 49 secured to bottom panel 41 in abutting relationship by staples or adhesive. A wrapped ham butt 26 is secured to the cradle by tapes 28 and 29. It is obvious that the outer panels 48 and 49 of the cradle shown in Figs. 11, 12 and 13 may be overlapped, as in Figs. 8, 9 and 10, if desired.

In the embodiment of Figs. 14, 15 and 16 the blank provides a bottom panel 50 with end panels 51 and 52 adapted to be folded upwardly at opposite ends thereof. End panel 51 has a pair of triangular side panels 53 and 54 foldable along a line coinciding with opposite sides of the end panel. A bottom flap 55 extends from one edge of panel 53, and a similar flap 56 extends from one edge of panel 54. At the opposite end of the cradle panels 57 and 58 and flaps 59 and 60 are similar to panels 53 and 54 and flaps 55 and 56, respectively. The cradle is assembled by folding end panels 51 and 52 upwardly at right angles to bottom panel 50. Side panels 53, 54, 57 and 58 are then folded inwardly at right angles to end panels 51 and 52, and finally flaps 55, 56, 59 and 60 are folded upwardly against the underside of bottom panel 50 and secured thereto by staples or adhesive.

The cradle of Figs. 14, 15 and 16 is suitable for packaging either a butt or shank, the only difference being that longer end and side panels are provided for shanks. In either case the end panels are pulled into close contact with the sides of the butt or shank by tape 28 and conform to the contour of the contiguous portion of the ham supported therein. The side panels 53, 54, 57 and 58 substantially increase the strength of the cradle because they resist movement of the adjacent portions of the cradle.

In the embodiment of Figs. 17 to 20 the ends of the cradle are provided with cushioning members. The blank comprises a single strip 61 of corrugated board or other suitable material scored to provide an end panel 62 at one end of the strip adapted to be secured at its free edge to the free edge of a side panel 63 at the opposite end of strip 61. Side panel 63 is separated from another end panel 64 by a fold line extending transversely of strip 61. A fold line at the opposite edge of end panel 64 separates it from another side panel 65 interposed between end panels 62 and 64. The free edges of end panel 62 and side panel 63 are secured together by adhesive tape, or either panel may be secured to the other by staples or other suitable fastening means.

Each of panels 62, 63, 64 and 65 is scored along a longitudinal line spaced from one edge of the panels a distance equal approximately to half the width of end panels 62 and 64 to form flaps 66, 67, 68 and 69. Each of these flaps is folded at right angles to the plane of its respective panel, and flaps 66 and 68 are secured to opposite ends of flaps 67 and 69, by staples or adhesive, to form a bottom for the cradle. Side panels 63 and 65 are duplicates, and only one will be described. The upper edge of each side panel is notched to provide a V-shaped recess 70 centrally of the panel. A slot 71 extending transversely of strip 61 from the bottom of notch 70 terminates in a longitudinal slot 72 which extends equal distances on both sides of slot 71 along a line at right angles to slot 71. Slot 72 is shorter than the width of the upper portion of notch 70 and is spaced a short distance above the fold line which separates bottom flap 67 from side panel 63.

Each side panel is provided with a pair of parallel fold lines on both sides of slot 71. One fold line of each pair extends diagonally from one end of slot 72 to the upper, outer end of the side panel closest thereto. The distance between the fold lines of each pair is approximately equal to one half the width of end panels 62 and 64. The side panels are folded inwardly along each of the diagonal

fold lines to form a pair of cushioning panels 73 adjacent each end of the cradle. Cushioning panels 73 extend angularly from the end panel to the outer end of slot 72. Slot 72 is preferably spaced from the bottom of the cradle to provide a short upstanding flange 74 which provides some rigidity to the side wall of the cradle. A flap 75 extends from the inner edge of each cushioning panel 73 to the adjacent end panel. Cushioning panels 73 are adapted to fit against the sides of a ham mounted in the cradle of this embodiment to provide a resilient support therefor.

The embodiment shown in Figs. 21, 22 and 23 is similar to that shown in Figs. 1 to 7. The blank, shown in Fig. 22, comprises a bottom panel 76 and end panels 77 and 78 at opposite ends thereof. Bottom reinforcing panels 79 and 80 extend from opposite edges of bottom panel 76 and are separated therefrom by short slots 81 and fold lines connecting the ends of aligned slots. Panels 79 and 80 are each folded inwardly to form three juxtaposed layers forming the bottom of the cradle. Ends 77 and 78 are folded upwardly at right angles and then corner portions 82 are folded inwardly with bottom flaps 83 interposed between bottom panel 76 and panels 79 and 80. Each flap 83 is provided with a notch 84 which engages the inner end of slot 81 to hold the corner pieces in place. Each corner piece 82 is provided with a pair of diagonal fold lines to provide trapezoidal cushioning panels 85 extending angularly between the end panels and the bottom. A flap 86 extends from each cushioning panel 85 to the adjacent end panel.

In the embodiment of Figs. 24 to 26 the blank is provided with an end panel 87 at one end, a side panel 88 adjacent said end panel, a second end panel 89, and a side panel 90 at the opposite end of the blank. The free edges of end panel 87 and side panel 90 may be secured together by adhesive tape, or either panel may be provided with a flap adapted to overlap the free edge of the other and to be secured thereto by staples or adhesive.

Each of panels 87, 88, 89 and 90 is scored along a longitudinal line spaced from one edge of the panels a distance equal to half the width of the end panels to form flaps 91, 92, 93 and 94 foldable inwardly to form the bottom of the cradle. Flaps 91 and 93 are secured to opposite ends of flaps 92 and 94 by staples or adhesive. Side panels 88 and 90 are duplicates. Each side panel is slotted to form a tab 95 foldable against the bottom of the cradle and secured thereto in any suitable manner. Diagonal fold lines 96 and 97 facilitate folding of the side panels to form trapezoidal cushioning panels 98 at each end with a flap 99 extending from each panel 98 to the adjacent end panel.

The embodiment of Figs. 27 to 29 is particularly adapted for the use of thin cardboard instead of corrugated board. The blank comprises a bottom panel 100 having end flaps 101 extending from opposite edges thereof and a side panel 102 adjacent one side separated therefrom by a fold line. End flaps 103 and 104 extend from opposite edges of panel 102. A top panel 105 extends from the side of panel 102 and has end flaps 106 extending from opposite ends thereof. A side panel 107 extending from the opposite side of top panel 105 has a flap 108 extending from its free side. End flaps 109 and 110 extend from opposite edges of panel 107.

Top panel 105 is provided with a pair of parallel fold lines 111 and 112 extending transversely thereof a short distance inwardly of the inner ends of end flaps 106. A small portion of panel 102 is cut away, as indicated at 113, and the panel is slit along diagonal lines 114 and 115 extending from the outer ends of cut out 113 to the closest end of score lines 111 and 112, respectively. Panel 107 is similarly cut and slitted. The blank is slit along line 116 from one cut out 113 to the

other. Side panels 102 and 107 are each provided with fold lines 117 and 118 extending angularly from slit 116 to slits 114 and 115 respectively.

Slit 116 divides the inner portion of side panels 102 and 107 and top panel 105 into two oppositely disposed symmetrical wing sections separated completely from the side panels and connected to the top panel along fold lines 111 and 112, respectively. These sections are each divided by fold lines 117, 118 and the fold lines defining the sides of top panel 105 into a center panel 119, two intermediate panels 120, and two terminal panels 121.

In order to set up the cradle of this embodiment, bottom panel 100 and top panel 105 are folded in parallelism and side panel 107 is folded parallel to side panel 102. Flap 108 is then adhered to the adjacent edge of bottom panel 100. End flaps 103, 104, 109 and 110 are folded inwardly to close opposite ends of the cradle. Center panels 119 are folded downwardly into contact with the angular edges of side panels 102 and 107. Panels 120 are folded into juxtaposition with adjacent side panels 102 and 107 and terminal panels 121 are folded into juxtaposition with end flaps 103 or 109. End flaps 101 are then folded upwardly and end flaps 106 are folded downwardly into abutting relationship in juxtaposition with terminal flaps 121. The abutting edges of end flaps 101 and 106 are secured together by adhesive or pressure sensitive tape 122 which extends around the sides and is adhered to the outer surface of panels 120. When a ham is placed in the cradle the panels 119 act as cushioning members. The ham may be secured to the cradle by bands 28 and 29 just as in the other embodiments.

The cradles illustrated in Figs. 17 to 29 are each designed for use with a ham butt. However, the structural features of each of these embodiments may be incorporated into cradles adapted for use with ham shanks. The only difference would be the different shape of the cushioning members and the side panels.

In the embodiment of the invention shown in Fig. 30, the cradle comprises a pair of strips 123 and 124 of paperboard superimposed and stapled together, as indicated at 125. The upper strip 123 is folded upwardly in contact with the edges of the ham shank 126 which is wrapped in a transparent protective wrapper 127. A band 128 of pressure sensitive tape, or other suitable material, is wrapped tightly around the outside of strip 123 and the lower portion of the wrapped shank, to secure the strip 123 and the ham shank against relative movement. The lower strip 124 is bent upwardly at right angles in the planes tangential to the outer edges of the ham shank and are juxtaposed against the upper ends of strip 123. A band 129 of pressure sensitive tape or other suitable material is wrapped tightly around the upper portion of the wrapped ham shank and the strip 124 to secure both strips 123 and 124 in place. If desired, the upper ends of strips 123 and 124 may be stapled together to prevent any slippage.

Although we have described preferred embodiments of our invention in considerable detail, it will be understood that the description thereof is intended to be illustrative, rather than restrictive, as many details of the structure may be modified or changed without departing from the spirit or scope of the invention. Accordingly, we do not desire to be restricted to the exact construction described.

We claim:

1. A ham display package comprising a cradle support having a flat bottom, a pair of end walls extending upwardly from opposite ends of said bottom, a plurality of cushioning members extending angularly between each of said end walls and said bottom, a ham of irregular shape seated on said support bottom, said support bottom being positioned with its center in approximate vertical alignment with the vertical center of gravity of the package so as to enhance the stability of the package by preventing the weight of the ham from exerting any substantial structural pressure against the cradle support.

2. A ham display package comprising a cradle support having a flat bottom, a pair of end walls extending upwardly from opposite ends of said bottom, a plurality of cushioning members extending angularly between each of said end walls and said bottom, a ham of irregular shape seated on said support bottom, said support bottom being positioned with its center in approximate vertical alignment with the vertical center of gravity of the package so as to enhance the stability of the package by preventing the weight of the ham from exerting any substantial structural pressure against the cradle support.

3. A ham display package comprising a cradle support having a flat bottom, a pair of end walls extending upwardly from opposite ends of said bottom, a plurality of cushioning members extending angularly between each of said end walls and said bottom, a ham of irregular shape seated on said support bottom, said support bottom being positioned with its center in approximate vertical alignment with the vertical center of gravity of the package so as to enhance the stability of the package.

4. A ham display package comprising a cradle support having a flat bottom, a pair of end walls extending upwardly from opposite ends of said bottom, a plurality of cushioning members extending angularly between each of said end walls and said bottom, a ham of irregular shape seated on said support bottom, said support bottom being positioned with its center in approximate vertical alignment with the vertical center of gravity of the package so as to enhance the stability of the package by preventing the weight of the ham from exerting any substantial structural pressure against the cradle support.

5. A ham display package comprising a cradle support having a flat bottom, a pair of end walls extending upwardly from opposite ends of said bottom, a plurality of cushioning members extending angularly between each of said end walls and said bottom, a ham of irregular shape seated on said support bottom, said support bottom being positioned with its center in approximate vertical alignment with the vertical center of gravity of the package so as to enhance the stability of the package by preventing the weight of the ham from exerting any substantial structural pressure against the cradle support.

6. A one-piece support cradle for holding an article of irregular shape in display position, said cradle comprising a flat bottom, a vertical end wall extending upwardly at each end of said bottom, and panels integral with each end wall and foldable relative to each of said end walls, said last mentioned panels being adapted to restrain relative movement between said end walls and said bottom.

7. A support for articles of irregular shape, said support comprising a flat bottom, two upstanding end walls, and a plurality of integral corner cushioning members extending angularly downwardly between each end wall and said bottom.

7. A one-piece support for articles of irregular shape, said support comprising a flat bottom, a pair of parallel end walls extending upwardly from opposite ends of said bottom, and an integral extension projecting laterally from opposite sides of each end wall, each of said extensions being foldable to provide cushioning members extending angularly downwardly between said end walls and said bottom of each end of said support.

8. A one-piece support for articles of irregular shape comprising a flat bottom, two end walls extending upwardly from opposite ends of said bottom, and a plurality of integral cushioning members at each end of said support, said cushioning members being individually flexible to conform to the shape of contiguous portions of an article mounted in said support.

9. A blank for forming a support which comprises a single sheet of paperboard cut and scored to provide a bottom panel, two bottom reinforcing panels of less length than said bottom panel, two end panels, and corner extensions projecting laterally from opposite sides of each end panel, each of said corner extensions comprising a triangular side panel, a bottom flap, a trapezoidal panel, and a triangular flap.

10. In a support member having a flat bottom and an upstanding end wall, a corner structure comprising an integral extension projecting laterally from said end wall and foldable to provide a triangular side panel having one edge contiguous to one side of said bottom and another edge disposed angularly between said end panel and said bottom, a cushioning panel folded inwardly at right angles from said angularly disposed edge, and a flap foldable downwardly from the inner edge of said cushioning panel.

11. A one-piece support for articles of irregular shape, said support comprising an elongated strip of material folded along transverse lines to provide a bottom, two upstanding end walls, cushioning members extending angularly from the upper edge of each of said end walls to said bottom, and a terminal panel extending from the lower edge of each of said cushioning members, said terminal panels being secured to said bottom.

12. A one-piece support for articles of irregular shape, said support comprising an elongated strip of material folded along transverse lines to provide a bottom, two upstanding end walls, cushioning members extending angularly from the upper edge of each of said end walls to said bottom, each of said cushioning members being arranged to conform generally to the shape of the contiguous portion of an article positioned in said support, and a terminal panel extending from the lower edge of each of said cushioning members, said terminal panels being secured to said bottom.

13. A support for articles of irregular shape, said support comprising a bottom panel, an end panel integral with one end of said bottom panel and foldable into upstanding position relative thereto, triangular side panels foldable at right angles to opposite sides of said end panel, and a flap integral with each of said side panels, said flaps being foldable into juxtaposition with said bottom panel and adapted to be secured thereto.

14. A support cradle comprising a pair of parallel side walls and a pair of parallel end walls, the free edge of one end wall being secured to the free end of one side wall to provide a hollow rectangular shape for said cradle, a flap foldable inwardly from the lower edges of each of said side walls and end walls, said end wall flaps being secured to opposite end portions of said side wall flaps to form a bottom, and each of said side walls being

cut and scored whereby portions thereof may be folded to provide cushioning members extending angularly between each end wall and said bottom.

15. A support cradle comprising a bottom panel having reinforcing panels foldable inwardly from opposite edges thereof, end panels foldable upwardly from opposite ends of said bottom panel, side panels foldable inwardly from opposite edges of each of said end panels, portions of said side panels being foldable inwardly to form cushioning members extending angularly from each of said end panels, and bottom flaps foldable upwardly from the lower edge of each of said side panels, said bottom flaps being insertable between said bottom panel and said reinforcing panels.

16. A support cradle comprising a bottom panel having reinforcing panels foldable inwardly from opposite edges thereof, end panels foldable upwardly from opposite ends of said bottom panel, side panels foldable inwardly from opposite edges of each of said end panels, and bottom flaps foldable upwardly from the lower edge of each of said side panels, said bottom flaps being insertable between said bottom panel and said reinforcing panels.

17. A support cradle comprising a bottom panel having reinforcing panels foldable inwardly from opposite edges thereof, end panels foldable upwardly from opposite ends of said bottom panel, side panels foldable inwardly from opposite edges of each of said end panels, portions of said side panels being foldable inwardly to form cushioning members extending angularly from each of said end panels, and bottom flaps foldable upwardly from the lower edge of each of said side panels, said bottom flaps being secured to said bottom panel.

18. A support cradle comprising a bottom panel, two parallel side panels, a top panel, a flap on one of said side panels adapted to be secured to said bottom panel to provide a hollow rectangular shape for said cradle, flaps foldable from opposite ends of each of said side panels to form end walls, and two oppositely disposed symmetrical wing sections cut from said side panels and connected to said top panel by fold lines, each of said wing sections being foldable across said cradle to form cushioning members at each end of said cradle.

19. A support cradle comprising a bottom panel, two parallel side panels, a top panel, a flap on one of said side panels adapted to be secured to said bottom panel to provide a hollow rectangular shape for said cradle, flaps foldable from opposite ends of each of said side panels to form end walls, and two oppositely disposed symmetrical wing sections cut from said side panels and connected to said top panel by fold lines, each of said wing sections being foldable across said cradle to form cushioning members at each end of said cradle, the terminal portions of said wing sections being secured between said end flaps.
